CUSHIONING DEVICE FOR SLICING MACHINES

Filed Jan. 28, 1928

UNITED STATES PATENT OFFICE

ANTON C. SENSOV, OF LA PORTE, INDIANA, ASSIGNOR TO U. S. SLICING MACHINE COMPANY, OF LA PORTE, INDIANA, A CORPORATION OF INDIANA

CUSHIONING DEVICE FOR SLICING MACHINES

Application filed January 28, 1928. Serial No. 250,101.

In hand-operated slicing machines in which the work support is reciprocated past the edge of the slicing knife, the work support often strikes the bracket supporting the slide rod resulting in a noisy and inefficient operation.

It is the object of this invention to provide a bumper construction which will effectively cushion the shock caused by the movement of the work support.

Another object of this invention is to provide an adjustable abutment member for changing the extent of travel of the substance table so that substances of different widths can be efficiently cut with a minimum travel of the table.

Another object of this invention is to provide a yielding means which is compressible at the end of the working stroke of the table so that the energy stored in said yielding means by the compression thereof may be utilized to start the return stroke as well as cushion the end of the working stroke.

A still further object of this invention resides in providing a cushioning means which is well protected by a covering which includes telescoping sections.

In the drawing—

Fig. 1 is a perspective view of a slicing machine embodying my invention; and

Figs. 2 and 3 are detail views showing modified constructions of the bumper.

Referring to Fig. 1, 10 represents the base of a machine from which rise the brackets 11 supporting the rods 12 and 12' at their ends. The sleeves 14 connected by a web portion (see Fig. 3) are slidably mounted on the rods 12 and 12' and the web portion 13 carries the work support 37. A handle 40 is provided to move the work support back and forth on the rods 12 and 12'. The machine shown in Fig. 1 includes a knife 32 and a meat table 32' and a slice receiver 48. The slice receiver 48 is connected with the support by brackets 47 and the slice receiver reciprocates with the work support. This construction is all shown in my co-pending application, Serial No. 141,901, filed October 16, 1926, and is only generally shown here to illustrate the application of my improved

bumper. On each end of the rod 12 is slidably mounted a cup-shaped abutment element 16 and a stationary abutment element in the form of a collar 18 is fixed on the rod 12 adjacent the end bracket 11. A spring 17 is interposed between these abutment elements and the member 16 may be made of some form of noise damping material, or a washer 15 may be provided made of fiber or other suitable material for damping the noise caused by the impact of the sleeve 14. It will be seen that when the sleeve 14 reaches the end of its stroke it will strike the cup-shaped member 16 compressing the spring 17 against the collar 18. The collar 18 is of smaller diameter than the recess in the cup-shaped member 16 and is adapted to be contained in the cup 16 when the cup 16 is moved by contact with the sleeve 14. The collar 18 is also normally positioned at the end of the recess or opening in the cup 16 and serves as a seal to prevent dirt or grease from getting on the spring 17. It is to be noted that the positions of the stationary element 18 and the movable cup-shaped element 16 might be reversed and the member 16 could be positioned with its open end facing the sleeve 14. The collar 18 will then receive the impact of the sleeve 14 compressing the spring 17.

In Fig. 2, an annular recess 19 is formed in the sleeve 14 and this recess is adapted to receive a stationary element or collar 18'. The recess forms an air pocket in which the air is compressed when the sleeve 14 is moved to envelop the collar 18'. The air pocket in the recess 19 forms a very efficient and economical cushioning means and, as shown, an air pocket 19 is positioned on each end of the sleeve 14.

In Fig. 3, the web portion 13 connecting the sleeves 14 is provided with oppositely directed recesses receiving springs 29, one of which is shown in Fig. 3. The spring 29 surrounds bolts 30 slidable in the recess and the bolts 30 each have a head or abutment element 28 at one end and one of these elements contacts with the bracket 11 and the other contacts with an adjustable member 20. The member 20 is slidably mounted on the rods 12

and 12' and is provided with a plunger 23 having a head 26 urged by a spring 25 into engagement with any one of the series of notches 27 in the rod 12.

5 By means of the adjustability of the member 20 longitudinally of the guide rods 12 and 12' I am enabled to vary the extent of travel of the carriage without destroying the effectiveness of the resilient means which 10 acts as a buffer at the ends of the path of movement of the carriage. It is very desirable in cutting narrow substances such as sausages and the like, to reduce the extent of the movement of the carriage so that the 15 stroke will be just sufficient to move the substance clear of the knife on the return movement of the carriage, thereby eliminating any extra or unnecessary motion of the carriage to effect a saving in time and energy.

20 In hand operated slicing machines, the carriage may be moved at any desired speed and when cutting substances which do not contain bones or in cutting substances which do not require a great amount of pressure to 25 be exerted on the table, the bumper construction is not utilized to its fullest extent as the operator can generally gauge his movements so that as soon as the cutting stroke is finished the pressure can be applied to the carriage in the reverse direction. However, when slicing substances containing bone, the operator pushes the carriage at a rapid rate toward the knife so that the knife will cut 30 through the bone and sever the bone as well as cut the slice from the meat. In cutting through bone, it is preferable to have the knife strike the bone with a relatively sharp blow as the bone is more readily cut in this manner, than with a slow slicing movement.

40 The action of the knife on the bone is similar to that of a meat cleaver. In cutting pork chops if the knife passes between two adjacent ribs the cutting force required is not as great as if the knife has to pass through 45 the rib itself. The operator, however, in moving the table must apply a sufficient amount of force thereto to enable the knife to cut through the rib itself. Therefore, if instead of passing through the rib it passes 50 through the bone cutting adjacent the ribs, some of the force exerted on the carriage is not utilized for the cutting stroke and as soon as the slice is entirely severed from the substance, the carriage continues the rapid 55 movement which must be cushioned in order to prevent damage to the carriage and its bearings. The excess force is utilized to help return the carriage to its original position.

60 It will be seen that the bumper construction generally comprises two elements one of which is stationary and the other of which is movable relative to the stationary member during the time the cushioning means is compressed. The movable element has a re-

cess therein into which the relatively stationary element is received. In Fig. 1, the relatively movable element is the cup 16 and the stationary element is the collar 18. In Fig. 2, the movable element is the recessed sleeve 19 receiving the stationary element at the time the cushioning action becomes effective and in Fig. 3 the web 13 of the sleeve 14 is the recessed relatively movable element receiving the stationary element 28 to compress 75 the spring 29.

I claim:—

1. In a slicing machine having a slicing knife and a work support, a slide rod upon which said work support is slidably mounted for reciprocation past the edge of said knife, said work support having oppositely directed recesses therein, a spring in each of said recesses, an abutment member against which one end of each spring bears, stationary contact members, said abutment members each having a contact face adapted to engage one of said contact members at the end of each reciprocative movement to compress said springs and yieldingly retard the motion of said work support, one of said contact members being adjustably mounted on said slide rod to vary the length of the path of reciprocative movement of said work support.

2. In a slicing machine, the combination with a carriage, of a slicing knife, guiding means for said carriage, said carriage being free to move along said guiding means when manual pressure is applied directly thereon, the extent of movement of said carriage being controlled at the will of the operator, and cushioning means arranged to be engaged by said carriage for stopping the reciprocating movement thereof and being movable to different positions of adjustment to selectively predetermine the position at which the movement of said carriage will be arrested, said cushioning means comprising telescoping members arranged one on said carriage and one on a fixed support, and a compressible means within said telescoping members adapted to be compressed as said telescoping members are moved relatively toward each other.

3. In a slicing machine, the combination with a carriage, of a guide rod upon which said carriage is slidably mounted, a recess in said carriage concentric with said guide rod, a member independent of said carriage and stationary with respect to said guide rod, surrounding said guide rod, manual means for directly actuating said carriage and for manually controlling the extent of movement thereof, said member surrounding said guide rod being adapted to enter said recess to cushion the movement of said carriage at one extent of its path of travel.

4. A device as set forth in claim 3 in which a second cushioning means is provided for cushioning the movement of said carriage

at the extent of its movement in the opposite direction, said second cushioning means being constructed similarly to said first cushioning means, and comprising a recess in said carriage concentric with said guide rod, and a member on said guide rod concentric therewith and adapted to enter said recess.

5 In testimony whereof I have signed my name to this specification on this 23rd day
10 of January, A. D. 1928.
